UNITED STATES PATENT OFFICE.

FRANK SCHULTE, OF PHILADELPHIA, PENNSYLVANIA.

DESIGN FOR A HALL-CLOCK.

52,711.

Specification for Design.

Patented Nov. 19, 1918.

Application filed August 22, 1918. Serial No. 251,038. Term of patent 14 years.

To all whom it may concern:

Be it known that I, FRANK SCHULTE, a citizen of the United States, residing at Philadelphia, in the county of Philadelphia, State of Pennsylvania, have invented a new, original, and ornamental Design for Hall-Clocks, of which the following is a specification, reference being had to the accompanying drawing, forming part thereof.

The figure is a perspective view of a hall clock showing my new design.

I claim:

The ornamental design for a hall-clock, as shown.

FRANK SCHULTE.
